United States Patent Office

Des. 186,879
Patented Dec. 22, 1959

186,879

BEAUTY PARLOR CHAIR

Edward Klein, Wilmette, Ill., assignor to Belvedere Products, Inc., Belvidere, Ill., a corporation of Illinois

Application November 26, 1958, Serial No. 53,537

Term of patent 7 years

Fig. 2 is a rear perspective view thereof.

I claim:

The ornamental design for a beauty parlor chair, substantially as shown.
